UNITED STATES PATENT OFFICE.

CHARLES F. SMITH, OF NEW BRITAIN, CONNECTICUT, ASSIGNOR TO THE LANDERS, FRARY & CLARK, OF SAME PLACE.

DESIGN FOR A TABLE-FORK.

SPECIFICATION forming part of Design No. 33,982, dated January 29, 1901.

Application filed January 2, 1901. Serial No. 41,833. Term of patent 7 years.

To all whom it may concern:

Be it known that I, CHARLES F. SMITH, a citizen of the United States, residing at New Britain, in the county of Hartford and State 5 of Connecticut, have invented and produced a new and original Design for Table-Forks, of which the following is a specification, reference being had to the accompanying drawings, forming part thereof.

10 Figure 1 is a plan view of a table-fork, showing my new design. Fig. 2 is a reverse plan view of the same. Fig. 3 is a central longitudinal section of the shank portion of the same, the other parts being shown in edge 15 view. Fig. 4 is a transverse section of the shank portion on the line xx of Fig. 1. Fig. 5 is a transverse section of the tines on the line yy of Fig. 1.

As shown in the drawings, the handle A is 20 of an ordinary form, and is therefore illustrated by broken lines. The tines 6 present an ordinary form in plan view; but in cross-section they have convex top and bottom sides with straight side edges, as shown in 25 Fig. 5. The contour of the shank 7 in plan

view shows a narrow neck, that abruptly widens in one direction toward the tines and in the other direction toward the handle. The upper face of the shank 7 is rounded over with a continuous plain smooth surface 30 of a convex form in cross-section, while there is a central groove 8 on the under side of the shank, the said groove being on a different curve and smaller than the said upper convex face. On each side of the groove at the 35 middle of the shank there is a plain portion 9, as best shown in Fig. 4, and the edges of the shank are straight, in harmony with the straight edges of the tines, as shown, respectively, in Figs. 4 and 5. 40

Having described my invention, what I claim as new, and desire to secure by Letters Patent, is—

The design for a table-fork, as herein shown and described.

CHARLES F. SMITH.
